DESCRIPTION

U.S. PATENT DOCUMENTS

D520,747 S * 5/2006 McClain D3/290
D651,794 S * 1/2012 Hargens D3/232

FIG. 1 is a top, rear perspective view of a handbag showing my new design;

FIG. 2 is a front elevation view thereof;

FIG. 3 is left side elevation view thereof;

FIG. 4 is a right side elevation view thereof;

FIG. 5 is a rear elevation view thereof;

FIG. 6 is a bottom plan view thereof; and,

FIG. 7 is a top perspective view of the handbag in an open configuration, the interior of the handbag forming no part of the claimed design.

The portions of the handbag shown in lighter contrast in FIG. 7 and surrounded by dash-dash broken lines do not form part of the claimed design.
